United States Patent Office.

ANDREW ERKENBRECHER, OF CINCINNATI, OHIO.

Letters Patent No. 67,514, dated August 6, 1867.

IMPROVED STARCH-ELEVATOR.

The Schedule referred to in these Letters Patent and making part of the same.

TO WHOM IT MAY CONCERN:

Be it known that I, ANDREW ERKENBRECHER, of Cincinnati, Hamilton county, Ohio, have invented a new and useful Starch-Elevator; and I hereby declare the following to be a full, clear, and exact description thereof, reference being had to the accompanying drawings, making part of this specification.

This invention relates to a device for conveying to an upper or distant room the moulded and separated blocks of partially solidified starch, so as to place the same convenient to the drying apparatus.

Figure 1 is a longitudinal section of a machine embodying my invention.

Figure 2 is a plan thereof.

A is a frame composed of two beams or shears B B' connected together by a web, affording journal-bearing for two rollers D D', of which the upper one, D, is the driver to an endless apron, E, which is stretched around both of them. F are rollers, which support the upper or effective side of the apron. G is a stand or trestle, affording journal-bearing for a series of rollers, H, which receive from the apron E, one after another, the boards I, on which the wet starch-blocks are placed. The trestle G is arranged at a proper height above the floor of the drying-room, for convenient removal, by the operatives, of the starch-laden boards to a suitable table. The wet blocks being lifted singly on to the drying-racks, the boards, as fast as empty, are placed edge-wise in the upper end of a trough, J, having a series of rollers, K, which enable the boards to descend to the place of commencement by their gravity, whence they are removed to a table in the lower story to receive fresh loads of wet starch.

By the above means I enable the safe, easy, and expeditious removal and elevation of the wet starch, free from the severe labor, wastage, and dirt-tracking which accompany the ordinary mode of elevation on the shoulders of a gang of laborers.

I claim herein as new, and of my invention—

The arrangement of ascending endless apron E, trestle G, and return-trough J, as and for the purpose set forth.

In testimony of which invention I hereunto set my hand.

ANDREW ERKENBRECHER.
